(57) **CLAIM**

The ornamental design for an automobile and/or toy replica
thereof, as shown and described.

DESCRIPTION

FIG. 1 is a front perspective view of an automobile and/or toy
replica thereof of our new design;

FIG. 2 is a rear perspective view thereof;

FIG. 3 is a rear view thereof;

FIG. 4 is a front view thereof;

FIG. 5 is a right side view thereof, the left side being a mirror
image thereof; and,

FIG. 6 is a top plan thereof.

The bottom view forms no part of the claimed design.
